UNITED STATES PATENT OFFICE.

BENJAMIN W. TUCKER, OF SOUTH ORANGE, NEW JERSEY, ASSIGNOR TO GEORGE E. HERMANN, OF MORRISTOWN, NEW JERSEY.

BARREL.

1,274,108.

Specification of Letters Patent. Patented July 30, 1918.

Application filed December 8, 1913. Serial No. 805,319.

To all whom it may concern:

Be it known that I, BENJAMIN W. TUCKER, a citizen of the United States, and a resident of South Orange, county of Essex, sex, and State of New Jersey, have invented certain new and useful Improvements in Barrels, of which the following is a full, clear, and exact description.

This invention relates more particularly to the construction of the ends of metallic barrels or other containers and the means whereby the heads may be detachably held to the container body.

One of the principal objects of the invention is to provide simple and efficient means whereby the body of the barrel may be made of a single piece of metal or of a plurality of staves which are of less length than the entire barrel when completed to adapt the heads when in use to pass about the ends of the staves or the barrel body, and to construct the barrel or container so that it will be very strong so as to take up all strains at the ends to which it may be subjected, and to permit bale hooks and the like to be used on the barrel without injury thereto and in a manner substantially the same as with the ordinary wooden barrel.

Other objects of the invention are to provide simple and efficient means whereby a metallic barrel may be constructed to have substantially the appearance of the ordinary wooden barrel with an enlarged central portion to adapt the same to be readily turned on end when desired; to provide means whereby either or both heads may be readily and securely held to the ends of the body in such a way that either head may be removed and after removal utilized as a cover for the barrel; and to provide simple and efficient means whereby the parts holding either or both heads in position may be interlocked and rigidly held in such locked position.

Another object of the invention is to simplify and cheapen the cost of construction and manufacture of barrels or other containers and at the same time materially strengthen the same.

A further object of the invention is to provide means whereby a barrel may be made of a knocked-down character and the parts, such as the staves, etc., when so knocked down by being of less length than

the barrel, may be packed within another empty barrel for shipment or transportation purposes.

With these and other objects in view, the invention will be hereinafter more particularly described with reference to the accompanying drawings, which form a part of this specification, and will then be pointed out in the claims at the end of the description.

In the drawings, Figure 1 is a fragmentary side elevation of one end of a barrel having a part thereof broken away and shown in section for the purpose of better illustrating the same.

Fig. 2 is a fragmentary sectional plan taken on the line II—II of Fig. 1.

Fig. 3 is a fragmentary section taken on the line III—III of Fig. 2.

Fig. 4 is an enlarged fragmentary section taken on the line IV—IV of Fig. 2.

Fig. 5 is a view similar to Fig. 4 except that the head has been removed and is shown in position to be used as a cover.

Fig. 6 is a detail perspective view of one of the hoops used for assisting in holding the head detachably to the end of the barrel body.

Fig. 7 is a detail perspective view of one of the members of the binding band which is adapted to interlock with a part of the hoop shown in Fig. 6 to bind the head to the barrel or container body.

Fig. 8 is a fragmentary view of one end of the barrel or container, partly broken away and partly in section, showing a somewhat different construction for holding the head to the barrel body.

Fig. 9 is an enlarged fragmentary vertical section of the construction shown in Fig. 8.

Fig. 10 is a fragmentary view, partly in section and partly in elevation, of a barrel having a somewhat different construction of means for holding the head to the barrel body; and

Fig. 11 is an enlarged sectional view of the construction shown in Fig. 10.

The barrel body 10 may be made of a single piece of sheet steel or other material or may comprise a plurality of staves 11 as shown, and said body may have the staves so formed that the body will be enlarged centrally thereof to adapt the bar-

rel when assembled to be readily placed on end or otherwise handled in a manner substantially the same as with the usual wooden barrel. Each stave, Figs. 1 to 7, at or near 5 the upper portion thereof is offset, as at 12, at either or both ends thereof so as to form a substantially U-shaped part 13 transversely of the stave adjacent to the end, which when the staves are assembled form 10 an interior rib 14 annular in form and which provides an annular groove 15 at either or both ends of the barrel body for a purpose to be presently described. The ends of the barrel staves lie substantially parallel to the 15 body portion of the stave and project beyond the annular rib 14, as at 16, and are offset from said rib a distance sufficient to provide a shoulder, as 17, against which is adapted to rest the lower edge of a solid 20 ring or band 18. This ring or band 18 fits within the barrel body end and against the interior surface of the ends 16 of the staves and serve to materially strengthen the end of the barrel.

25 A head 19 is located at either or both ends of the barrel body and though only one end of the barrel and the construction thereof is shown, it will be understood that both ends of the barrel or other container 30 may be similarly constructed. Each head has a substantially flat disk-like body 20 with a flange 21 projecting outward therefrom and which is at an angle with respect to the body portion so as to be flared outward to fit the exterior of the staves and 35 tend to force the same against the solid ring or band 18. The heads as thus constructed will fit about the outer ends of the staves, or the barrel body if made of a 40 single piece of metal, and the barrel staves are thus made of less length than the length of the entire barrel when assembled so that the ends of the staves are not directly subjected to strains and impact and 45 are less likely to be injured, at the same time adapting the barrel to be readily knocked down and when in this condition, by reason of the length of the staves, the latter may be placed within an empty barrel 50 for reshipment or transportation.

Various means may be employed for detachably holding either or both heads of the barrel to the barrel body. As one means, I show a divided member 22 which may 55 comprise two or more parts and these parts when placed together form a ring or band which is adapted to fit in the groove 15 formed by the interior rib or offset portion. The member 22 may be of heavier metal 60 than the barrel body itself and may be formed as shown or pressed into shape in any suitable way, and each part of the member 22 has grooved projecting portions 23 which alternate with spaces 24, the said 65 spaces and projecting portions alternating

throughout the entire extent of the member 22. A hoop or holding member 25 is provided which may be also of heavy metal and solid or divided as preferred but ordinarily made solid. This hoop or member 70 25 has its outer end enlarged to provide an overhanging portion 26 which is adapted to fit upon the outer surface and over the head to hold the head against detachment until the hoop member 25 is removed. This part 75 26 forms a chimb which projects beyond the head and serves as a means for taking immediate impact when the barrel is placed on end and also to adapt the same for the use of bale hooks, etc., similar to that of the 80 ordinary wooden barrel. The member 25 tapers or is flared to correspond to the inclination or shape of the barrel or other container and is adapted to fit along the flange portion 21 of the barrel head serving to 85 force the same into close contact with the ends of the barrel staves, and said member has grooved projecting portions 27 and spaces 28 between said grooved projecting portions. The grooved projecting portions 90 27 are adapted to fit in the spaces 24 of the member 22 and the grooved projecting portions 23 of said member 22 are adapted to fit into the spaces 28 of the member 25 so as to interlock with each other, yet permitting the member 25 at either end of the barrel to be quickly removed or placed in position. The grooved projecting portions 27 of the member 25 and the grooved projecting portions 23 of the member 22 are 95 100 adapted to be brought into alinement and when in this position a wire or band 29 or other fastening element may be passed about the member 22 and the member 25 within the grooves of the projections 23 and 105 27, thus firmly and rigidly locking the members together and serving to hold the head against removal. It will be evident that the head may be readily detached by removing the fastening element 29 although, unless entirely removed, it will be necessary to shear the wire in more than one place through accident or otherwise before the hoop member 25 could be detached to permit the removal of the head. By employing a construction as shown, a very 110 115 strong and efficient barrel is provided and one which will effectually take up the strain to which barrels are ordinarily subjected.

In some instances, the contents remain in the barrel, as for example sugar, and it is usually desirable that a cover be provided to close the open end of the barrel. In the construction shown, either head of the barrel may be removed and the same head utilized as a cover by having the same fit over the hoop member 25, as shown in Fig. 5, thus the head may be used both as a permanent closure for the barrel or as a cover therefor.

In Figs. 8 and 9, the staves 30 have the ends thereof offset, as at 31, to form a shoulder 32 and an outwardly extending part or flange 33. A ring or band 34 similar to the band or ring 18 is provided which fits within the ends of the barrel staves and rests upon the shoulder 32 formed by the offset portions 31. The head 35 in this case has an outwardly flared flange which is adapted to fit about the ends of the barrel staves. A divided or split ring or member 36 is adapted to fit about the head and end of the barrel. This hoop or member 36 has a straight portion 37 along the outer edge of which is a depressed grooved part 38 which is adapted to rest upon the outer surface of the head 35 serving to retain the same against outward movement, and adapted to fit in said grooved portion is a wire band or fastening element 39 which serves to assist in holding the ring or parts thereof against separation. The member 36 has a shoulder or offset portion 40 which is adapted to fit under the offset portion 31 of the staves and fitting under said shoulder is a fastening element or wire 41 which assists in holding the member 36 to the barrel body, and also prevents its removal therefrom and serves to rigidly hold the barrel head to the barrel body. In this case as in the other form, the flange of the head may be so made as to fit neatly and so as to be forced over the ends of the barrel staves to force the ends of said staves against the ring 34, thereby adapting the end of the barrel to be materially strengthened. By detaching or separating the wire 41 and the wire 39, the member 36 if split may be spread far enough to be removed, or if divided may be separated entirely to adapt the head to be detached so that access may be had to the barrel or any other container to which these features may be applied.

In Figs. 10 and 11, a somewhat different construction is shown. In this case, the staves 42 at their ends are curved inwardly, as at 43, and then outwardly to provide an exterior shouldered groove 44 and an interior shoulder 45 which is annular in form when the staves are assembled. A ring or band 46, which may be solid, rests upon the shoulder 45 within the stave ends or within the barrel body when the latter is made of a single piece, and fitting over the ends of the staves and over the band 46 is a head 47 which is constructed and arranged substantially the same as already shown and described. The hoop or member 48 may be split or divided into parts and has an overhanging portion 49 which is adapted to fit over the outer surface of the barrel head to hold the same against removal and has a grooved part 50 and a shouldered part 51, the latter fitting against the curved part 43 and within the shouldered groove 44 serving

to prevent the ring or member 48 from being detached by accident or the like. In the groove 50 is arranged one or more fastening wires or elements 52 which serve to hold the split ring or hoop or the parts thereof if divided, in position and against accidental detachment unless said wires or fastening elements are removed.

It will be understood that while the invention is shown as applied to a barrel of a particular form comprising staves, the said invention may be applied to various forms of containers or barrels in which the body portion may be variously constructed, and it will be further understood that any suitable means may be provided for interlocking and holding the staves together along the edges and about the body of the barrel intermediate the ends of the barrel body as is provided in some instances in inventions of this kind.

From the foregoing, it will be seen that a simple, strong and efficient closure and means for holding the same is provided for barrels or other containers; that simple means is provided for detachably holding either or both heads to the barrel body and of such a nature as will assist in materially strengthening the barrel at its ends and to take the impact thereof; that the said construction permits the heads to be detached and used as a cover if desired; and that by having the barrel staves of less length than the body itself the barrel may be knocked down and the staves put in another barrel for shipment, thus materially saving expense and at the same time protecting the staves against injury during such transportation.

Having thus described my invention, I claim as new and desire to secure by Letters Patent:—

1. A metallic barrel or container having a body comprising a plurality of staves each having an offset portion forming an annular grooved rib, a band resting upon said rib within the end of the barrel body, a divided member having grooved projections spaced apart and arranged within the groove of the annular rib, a head fitting over the ring and the ends of the staves, a retaining hoop member having grooved projecting portions fitting the spaces of the divided member and provided with an overhanging part forming a chimb for the barrel and resting against the outer surface of the barrel head to hold the same against removal, and a wire band for holding the divided grooved member and the hoop member interlocked.

2. A metallic barrel or container comprising a body having an offset portion forming an annular grooved rib, a solid band resting upon said rib within the end of the barrel body, a divided member arranged within the groove of the annular rib, a head fitting over the ring and the end of the body,

and a retaining hoop member having means to interlock with the divided member and provided with an overhanging part resting against the outer surface of the head to hold the same against removal.

3. A container comprising a body, a band located within the end of the container body, an annular member extending about the container body exteriorly thereof, a head provided with a flared flange fitting over the ring and the end of said body adapted to be removably held therein, a retaining hoop member having an overhanging part forming a chimb for the container and resting against the outer surface of the head to hold the same against accidental removal, and a wire band for detachably holding the annular and hoop members to the barrel body.

4. A metallic container having a body comprising a plurality of staves each having an offset portion forming an annular rib, a solid band resting upon said rib within the end of the staves, an annular member having grooved projections spaced apart and located on the exterior of the body, a head fitting over the ring and the ends of the staves, a retaining hoop member having grooved projecting portions fitting within spaces of the annular member and provided with means to rest against the outer surface of the head to hold the same against removal, and a wire band for holding the annular grooved member and the hoop member interlocked.

5. A metallic container comprising a body having an offset portion forming an annular grooved rib, a solid annular band resting upon said rib within the end of the container body, a divided member having grooved projections spaced apart and located on the outside of the container, a head fitting over the ring and the end of the body, a retaining hoop member having grooved projecting portions fitting the spaces of the divided member and provided with an overhanging edge resting against the outer surface of the head to hold the same against removal, and a wire band for holding the divided grooved member and the hoop member interlocked.

6. A metallic barrel comprising a plurality of staves forming a body and having their ends offset to provide a shoulder, a solid ring arranged within the offset portion of the staves, a head having a flange fitting over the ends of the staves and the ring and tending to force the ends of the staves against the ring, and means for holding the head detachably to the barrel body.

7. A metallic barrel comprising a plurality of staves forming a body, a solid ring arranged within one end of the body, a head having a flange fitting over the ends of the staves and the ring and tending to force the ends of the staves against the ring, and interlocking means embracing the head

flange for holding the head detachably to the barrel body and clamping said flange against the staves.

8. A metallic barrel comprising a body having an offset end, a ring arranged within said offset end, a head having a flange and fitting about the body at its end and directly against the same, and annular fastening means for detachably holding the head to the barrel body.

9. A metallic barrel comprising a body having an offset end, a ring arranged within said offset end and resting against the offset part of said body portion, a head having a flared flange fitting about the end of the body, and annular interlocking fastening means for detachably holding the head to the barrel body.

10. A metallic barrel comprising a body having an offset end, a ring arranged within said offset end and resting against the offset part of said body portion, a head, and annular fastening means for detachably holding the head to the barrel body.

11. A metallic barrel comprising a plurality of staves having an offset annular grooved rib, a solid ring fitting within the ends of the barrel body and resting against the grooved rib, a divided ring fitting within the groove of the rib, a head fitting over the end of the barrel body and over the ring and tending to force the ends of the staves against said ring, a solid hoop member having an overhanging portion forming a chimb for the barrel and as means to hold the barrel head in position, said hoop member having means to interlock with the divided member, and means for holding the hoop member and the divided member against detachment.

12. A metallic barrel comprising a plurality of staves having an offset annular grooved rib, a solid ring fitting within the ends of the barrel body and resting against the grooved rib, a divided ring fitting within the groove of the rib, a head fitting over the end of the barrel body and over the ring and tending to force the ends of the staves against said ring, a solid hoop member having an overhanging portion to hold the barrel head in position, said hoop member having means to interlock with the divided member, and a wire band for holding the hoop member and the divided member against detachment.

13. A metallic barrel comprising a plurality of staves, a solid ring fitting within the ends of the barrel body, a divided ring fitting within the groove of the rib, a head fitting over the end of the barrel body and over the ring and tending to force the ends of the staves against said ring, a solid hoop member having an overhanging portion to hold the barrel head in position, said hoop member having projecting parts to interlock

with the divided member, and means for holding the hoop member and the divided member against detachment.

14. A barrel or container comprising a body having an annular external shoulder adjacent one end thereof, an annular member arranged under said shoulder, a head fitting over the end of said body, an annular retaining member having an overhanging part resting against the outer surface of the head to hold the same against removal, and means for detachably locking said annular members together.

15. A metal barrel or container comprising a body having an offset portion forming an annular shoulder on the interior and exterior of the body, an annular reinforcing member resting upon the internal annular

shoulder within the end of the body, a head fitting over the end of the body and having a depending annular flange embracing the exterior of the body opposite said reinforcing member, and annular interlocked fastening devices for detachably locking the head to the body, one of said devices engaging the outer surface of the head and embracing head flange and the other of said devices engaging the under side of the external shoulder on the body.

This specification signed and witnessed this fifth day of December, A. D. 1918.
